FLUORESCENT TUBE SIGN

Edward John Faltings, Brooklyn, N. Y.

Application November 14, 1940, Serial No. 365,691

1 Claim. (Cl. 40—130)

This invention relates to a fluorescent tube sign and has for an object to provide a sign including a light source in the nature of a fluorescent tube which may be operated from a 110-volt current supply and which will form the background of advertising matter applied direct to the tube without the use of sleeves having cut-outs forming the advertising matter.

A further object is to provide a fluorescent tube sign which in addition to employing the tube as a background for the advertising matter also employs the tube to illuminate a base for the tube, the base having advertising matter displayed thereon and attached thereto, illuminated simultaneously with the advertising matter on the tube itself.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming a part of this specification:

Figure 1 is a front elevation of a fluorescent tube sign constructed in accordance with the invention.

Figure 2 is a rear elevation of the sign shown in Figure 1.

Figure 3 is an end elevation of the sign showing advertising matter carried by the base and illuminated by the tube.

Figure 4 is an end elevation of a modified form of the invention showing the front side of the base as vertical instead of sloped as in Figure 3.

Referring now to the drawing in which like characters of reference designate similar parts in the various views, 10 designates a fluorescent light tube adapted to be excited by a 110-volt current and including spaced terminal supporting socket members 11 formed integral with standards 12 which are mounted in any preferred manner on a base 13. Advertising matter 14 is applied to the tube, in the nature of a silhouette formed by painting or otherwise applying the same direct to the glass tube so that the light emitted by the tube when energized forms a background for the advertising matter and at

the same time is permitted to shine in all directions around the tube without obstruction so as to illuminate merchandise on display as well as other advertising matter carried by the base.

5 The base 13 is in the nature of an elongated box having the front wall 14' sloped downwardly and forwardly, or the front wall may be vertical if desired as shown at 15 in Figure 4. Where the front wall is sloped as shown in Figure 3 the standards 12 are set close to the front edge of the top wall 20 as indicated by broken lines. The light from the tube may illuminate advertising matter 16 on the front wall of the base.

10 15 A pair of spring clips 17, formed of strap metal, are secured by screws 18, or other connectors, to the rear wall of the base as best shown in Figure 2. These clips may be used to support a placard 19, as shown in Figure 4, displaying advertising matter or may be used to secure a display stand 20', of inverted U-shaped contour, to the base. The display stand is provided with a sloped top 21 upon which an article 22 of merchandise may be supported to be illuminated by the fluorescent tube.

20 25 From the above it will be seen that the fluorescent light tube displays advertising matter without the use of cut-outs so that the light from the tube is unobstructed and may illuminate advertising matter carried in front of, and in rear of the base as well as illuminate merchandise adjacent to the tube.

30 35 From the above description it is thought that the construction and operation of the invention will be fully understood without further explanation.

What is claimed is:

A sign comprising, a horizontally disposed 40 fluorescent tube, a base, spaced terminal supporting socket members on the ends of the tube, standards integral with the socket members secured to said base, said base being an elongated box having a front wall sloped downwardly and forwardly and displaying matter 45 forming a sign, the standards being disposed close to the front edge of the top wall of the box to dispose the tube to illuminate the sign on the sloped front wall by light rays from the bottom of the tube, a placard securing means 50 secured to the rear wall of the base, and a placard supported in vertical position by said means extending above the top wall of the base and adapted to be illuminated by light rays from the back of the tube.

EDWARD JOHN FALTINGS.
